UNITED STATES PATENT OFFICE

164,783

PERSONALIZED WEDDING ANNIVERSARY
CANDLE

Leo Lion, New York, N. Y.

Application January 24, 1950, Serial No. 7,451

Term of patent 7 years

(Cl. D73--1)

To all whom it may concern:

Be it known, that I, Leo Lion, citizen of the United States of America, residing at New York, in the county of New York and State of New York, have invented a new, original, and ornamental Design for a Personalized Wedding Anniversary Candle, of which the following is a specification, reference being had to the accompanying drawing, forming part thereof.

In the drawing:

Fig. 1 is a side elevational view of a personalized wedding anniversary candle, showing my new design.

Fig. 2 is a developed plan view showing the surface ornamentation thereon drawn to a larger scale, and

Fig. 3 is a top plan view of the personalized wedding anniversary candle shown in Fig. 1.

I claim:

The ornamental design for personalized wedding anniversary candle, as shown.

LEO LION.
